UNITED STATES PATENT OFFICE.

FRANK A. LUNDQUIST, OF CHICAGO, ILLINOIS, ASSIGNOR TO M. E. RICHARDSON, TRUSTEE, OF STERLING, KANSAS.

AUTOMATIC TELEPHONE-EXCHANGE.

SPECIFICATION forming part of Letters Patent No. 776,524, dated December 6, 1904.

Application filed April 30, 1900. Serial No. 14,824. (No model.)

To all whom it may concern:

Be it known that I, FRANK A. LUNDQUIST, a citizen of the United States of America, and a resident of Chicago, county of Cook, and State of Illinois, have invented certain new and useful Improvements in Automatic Telephone-Exchanges, of which the following is a specification.

My invention relates to automatic telephone-exchanges, and more particularly to the switching mechanisms in the central office and the manner in which they are electrically connected to each other.

The objects of my invention are to improve the central-office devices and to improve the manner of making electrical connections to these devices.

In the accompanying drawings, Figure 1 is a front elevation of a switch. Fig. 2 is a rear elevation of the same. Fig. 3 and Fig. 4 are side elevations from opposite directions. Fig. 5 is a section substantially on line 5 5 of Figs. 1 and 2. Fig. 6 is a section on line 6 6 of Figs. 1 and 2. Fig. 7 is a detail in plan, partly in section, of some of the parts illustrated in Fig. 1. Fig. 8 is a diagram showing the electrical connections when an auxiliary switch is used in connection between two main switches. Figs. 9 and 10 and 11 taken together are a general diagram showing the groups of main switches and auxiliary switches with three instead of ten taken as a basis. Fig. 12 is an abridged diagram, showing the talking-circuit between two telephones so as to illustrate the complete metallic connection from one to the other without going through any common return used by other telephones. Fig. 12 also shows a device whereby cross-talk by induction is prevented in the talking-circuit, and Fig. 13 is a perspective detail.

In the said drawings, 20 represents a vertical frame on which there are the shelves or brackets 21, 22, and 23. Mounted on these brackets is a shaft 28, on which there is a ratchet-wheel 24 and a cylindrical ratchet-rack 25. There are also on shaft 28 two gears 26, which mesh into racks 27, which racks are supported on rods 29, guided in slots in brackets 22 and 23. Secured to the racks 27 is a car-

riage frame or plate 30, to which are insulat- 50 ingly connected contact-makers 66 and 92.

On the frame 20, back of the shaft 28 and in the path over which the carriage 30 moves, is an insulating-block 49, having two groups of rectangularly-arranged contact-points 48 55 and 47. These are so arranged that when the carriage 30 is moved the contact-maker 92 is moved over the contact-points 48 and the contact-maker 66 is correspondingly moved over the contact-points 47. 60

Secured to the back of the frame 20 is a magnet A, having an armature-lever A², on the end of which is a pawl A³, adapted to engage the cylindrical ratchet 25 to move the shaft 28 upward, and consequently to carry upward the 65 carriage 30 and all the parts connected thereto. The pawl A³ has a wire A⁴ projecting from its side in a position to engage another wire A⁵, which is supported in the bracket 22. The parts A⁴ and A⁵ are so arranged that when 70 the magnet A is not energized they will keep the pawl A³ out of engagement with the cylindrical ratchet 25. Also secured on the back of the frame 20 is a magnet B, on the armature-lever B² of which there is a pawl B³, 75 adapted to engage the ratchet-wheel 24 for the purpose of turning the shaft 28, and consequently the gears 26, so as to move laterally the carriage 30. Wires B⁴ and B⁵ keep the pawl B³ out of engagement with the ratchet-wheel 24 when the magnet B is not energized. Another wire B⁶ serves as a stop for armature-lever B² in one direction, and a block B⁷ on the frame 20 serves as a stop in the other direction. 80

Supported on the bracket 22, near the cylinder-rack 25, is a post E, in which is pivoted a holding-pawl E', adapted to engage the ratchet 25 and prevent the downward movement of the shaft 28 until the said pawl has been released, as will be hereinafter described. 85

On the top of the frame 20 is a magnet C, which has an armature-lever C². The lower end of C² is near the lower end of the magnet C and is provided with a hook C³, which is adapted to engage a similar hook or catch on 95 a lever J', that is fitted in a post J on top of the frame. The forward end of J' projects underneath a collar secured on the upper end

of the shaft 28. When the shaft 28 is at its lowest position, this collar engages the lever J' , so as to raise its rear end clear of the hook C^3 on the armature-lever C^2 . When, however, the shaft 28 has been moved upward one step or more, the rear end of the lever J' descends, so that if the magnet C be energized the hook C^3 will engage the lever J' and hold the armature-lever C^2 in its attracted position.

10 Insulatingly secured to the armature-lever C^2 is a metal strip 51, which projects downward and is normally in contact with another metal strip 52. When, however, the magnet C is energized, the movement of the armature-lever C^2 moves 51 into contact with the other metal strip 86. When the hook C^3 is engaged and held by lever J' , the metal strip 51 is held away from strip 52 and into engagement with the strip 86. As this holding of 51 in contact with 86 can only occur when the shaft 28 has been moved upward from its lowest position, it will be evident that if the shaft be permitted to drop to its lowest position the contact between the collar on the upper end 25 of said shaft and the lever J' will release the hook C^3 and permit 51 to again move into connection with 52. Also on the upper portion of the frame is a magnet D, having an armature-lever D^2 similarly provided with a strip 30 59, which is moved into contact with a metal contact-point 114 when magnet is energized. Pivoted at F on the frame 20 is a lever F' , in the lower end of which is pivoted a second lever F^2 , that projects forward into the path 35 of the armature-lever A^2 and also into that of a lateral projection E^2 on the pawl E' . The lever F' is normally held to the right by a spring wound around the post F and shown in Fig. 7 as having its end extending over the 40 face of said lever. Also pivoted to the lever F' is another lever F^3 , the end of which has a hook adjacent to the armature-lever B^2 . (See Fig. 7.) From lever F^3 a rod D^3 projects upward and is connected to the armature-lever 45 D^2 , so that when the magnet D is energized the lever F^3 is moved with its hook in front of the armature-lever B^2 . If while in this position the magnet B be energized, the movement of the armature-lever B^2 will move the 50 lever F' to the left, so that a notch in the lever F^2 will engage the projection E^2 on the pawl E' . If after this action the magnet B be deenergized, the return movement of the lever F toward the right will draw the pawl 55 E' out of engagement with the ratchet 25, so as to permit the shaft 28 to drop by gravity to its lower position. As will be seen by inspection of Fig. 7, the same result will be accomplished by energizing magnet A, so as to move the 60 armature-lever A^2 upward instead of energizing the magnet D, because such movement of the armature-lever A^2 would move the hook on lever F^3 in front of the armature-lever B^2 , so that movement of B^2 to the left would in 65 the manner described cause F^2 to engage E^2 ,

so as to release the pawl E' . It will therefore be apparent that by simultaneous action of magnet B with either magnet A or magnet D the pawl E' is released from the ratchet 25, so as to permit the shaft 28 to fall to its lowest 70 position.

Pivoted on the bracket 21 and in a post K is a wide-faced pawl K' , adapted to engage the ratchet-wheel 24 when said wheel has been moved upward one step. In its lowest 75 position, as shown in Figs. 1 and 3, the ratchet-wheel is clear from pawl K' and may be moved to its normal position, as will be described.

Pivoted on a lug H at the lower end of the 80 frame 20 is a rod H' , to the lower end of which rod is pivoted a link H^2 , having its other end pivoted to a step-block H^3 for the shaft 28.

Surrounding the lower end of the shaft 28 85 and having one end secured to said shaft and the other to the step H^3 is a spring H^4 , the action of which is to return the shaft 28 to its normal position when the ratchet-wheel 24 is released from its pawl K' .

90 Secured on a portion of the armature-lever A^2 are a series of contact-makers 68, 87, and 117, which are adapted to engage, respectively, the contact-strips 63, 88, and 118. The armature-lever A^2 in its normal position 95 is in engagement with another contact-strip 56. The use of these various contact-strips will be more readily understood in the description of the circuits as they are illustrated in Fig. 8 and as they will be hereinafter described.

100 In operating the switch the magnet A is first operated to move the shaft 28 upward one step. The operation, or rather the movement, of the armature-lever A^2 raises the lever F^2 clear of the projection E^2 on the pawl E' , so as to permit the said pawl to drop into engagement with the ratchet 25 and hold the shaft 28 in its upward position when the magnet A is released. The upward movement of the shaft 28 brings the ratchet-wheel 24 into line with the pawl K' , so that when the magnet B is energized to turn the ratchet 24 the said pawl will prevent backward movement. The ratchet 24 may be turned any required number of steps after the shaft 28 has been moved upward one step and before it has been moved upward a second step. When, however, the shaft 28 has been moved upward 110 two steps, the ratchet 24 passes out of the path of the pawl B^3 , so that further operation of the magnet B does not affect the shaft 28. Assuming that by the successive operations of magnets A and B the shaft 28 has been moved upward several steps and also has been 115 rotated several steps, then by the successive and simultaneous operation of the magnets A and B or magnets D and B the hook on the lever F^3 will be pushed upward by magnet A and magnet D into the path of the armature- 120

125 or magnet D into the path of the armature- 130

lever B², so that by the action of the magnet B the lever F² will hook upon the projection E² on the pawl E'. Then upon the release or breaking of the circuits through the two operated magnets the lever F', and consequently the lever F², will be moved to the right, as shown in Fig. 7, drawing the pawl E' out of engagement with the ratchet 25. The shaft 28 will then fall by gravity to its lowest position, at which lowest position the ratchet-wheel 24 passes out of engagement with the pawl K', which permits the spring H⁴ to return the shaft to its normal position, which normal position is determined by a pin H⁵ on the shaft 28 coming in contact with a post H⁶ on the lower part of the switch. It will be observed that in this construction and arrangement the return movement of the shaft to its lowest position and also to its rotative position does not occur until after the electric circuits are broken through the two operated magnets. While it would be immaterial mechanically whether the return occurred before or after the breaking of the circuits through the magnets, it does make a difference in this case, because in the grouping of electric switches, as will be hereinafter described, if the return should take place before the circuits are broken such return would of itself break some other circuits before the operation is completed.

In arranging an electrical exchange I used one switch like that described for each telephone of the exchange. Assuming that the number of contact-points in one of the groups 47 or 48 is equal to one hundred, then the capacity of the switch would be for one hundred telephones in the exchange, provided that there are direct connections from one switch to the other. In the present drawings, however, I have illustrated main switches and auxiliary switches. The main switch is made according to the drawings illustrated and has contact-points thereon, as will appear in the description of the circuits. The auxiliary switches are substantially the same, except that the magnets C and D are omitted and a magnet G, as shown in Fig. 8, is arranged for the purpose of making certain electrical connections on the auxiliary switch. There is also a slight difference in the electrical connections to a main switch and to an auxiliary switch. Assuming one hundred contact-points on each group of contact-points on the main switch and auxiliary switches and arranged as shown in the diagrams, these switches may be used to a capacity of one thousand telephones in the exchange. The difference between direct connections between the switch belonging to one telephone and similar switches belonging to other telephones and connections through auxiliary switches in the manner shown may be illustrated as follows: With a switch having one hundred contact-points in one group in direct connection the

capacity will be for one hundred telephones. If, however, I use the same switches in ten groups of one hundred in each group, then supply ten auxiliary switches for each group, I have one thousand and one hundred switches, each of which has one hundred contact-points in one of its groups. If I made the same switches for one thousand capacity by direct connection, I should have to have one thousand contact-points in each group. There would therefore be for direct connection one thousand multiplied by one thousand, equal to one million contact-points on the switches to accomplish this result. By the grouping method, however, using auxiliary switches, I have one thousand one hundred switches with one hundred contact-points each, which will give a total number of contact-points of one hundred and ten thousand as against one million contact-points.

In carrying out an exchange involving auxiliary switches I arrange the central office as illustrated in Figs. 9, 10, and 11, in which there is a main switch for each telephone in the exchange and a group of ten auxiliary switches for each one hundred of said main switches. The diagram, however, shows the grouping abridged in number, but on the same general plan. This abridgment takes three instead of ten as the basis. Hence a group of main switches takes three times three or nine main switches, and the corresponding group of auxiliary switches is three in number. The diagram shows one group of main switches and part of a second group. It also shows the first and second groups of auxiliary switches and a numbered series of telephones corresponding to the main switches. There is a bank of wires 106 and 111, arranged in pairs, which serve as connections between the branches 105 and 112 (which run to contact-points on the auxiliary switches) and the branches 107 and 110, which connect to the normal contact-points on the main switches. A second bank of wires 69 and 94, also arranged in pairs, serve as connections between the branches 67 and 93 (which ran to contact-points on the main switches) and branches 71 and 78, which run to the contact-makers 72 and 104 on the auxiliary switches. There extends from one pole of the battery X a wire 100, which is provided with branches running to the operating-magnets on the main and auxiliary switches. The wire 101 extends from the other pole of the battery X and has branches extending to the telephones No. 1, No. 2, &c. From each telephone there extend the wires 50 and 55 through several intermediaries to the contact-makers 66 and 92 on the corresponding main switches. The intermediaries between the telephones and their contact-makers are omitted in the general diagram, but are shown in detail in Fig. 8. Referring to Fig. 8 and assuming that a subscriber at the telephone V (shown at the left hand of the drawing) wishes to talk to some other

one—as, for example, the telephone shown at the right hand of the drawing—then the operation would be as follows: The calling subscriber closes a contact marked “1st” at his 5 telephone, which sends an electrical impulse through the magnet A of his switch. The operation of A moves the shaft 28 one step and closes the connection between said shaft, which is in electrical connection with the base of the 10 switch to an insulated contact represented by a post 58 in Fig. 8 and by a metallic strip 58 in Fig. 1. He then closes another contact marked “2nd” at his telephone, which sends an electrical impulse through the connection 15 which is made and through the magnet B, which rotates the shaft 28 to move his contact-makers 66 and 92 laterally. He repeats this electric circuit through the magnet B as many times as is required to bring the contact-makers 20 opposite the required vertical rows of contact-points. He then makes ten successive electrical connections through the magnet A, precisely as in the first place, moving the contact-makers upward on their respective rows. As 25 soon as these contact-makers reach the contact-points which are in electrical connection with an unemployed auxiliary switch there are set up two other electric circuits, one of which automatically stops his own switch opposite these connections, so that the contacts he is making at his telephone no longer move the contact-makers upward. The second electrical circuit passes through the unemployed auxiliary switch which is thus selected and 30 automatically moves it to a position so that another switch cannot reach it. He then follows by a series of contacts made in his telephone to energize magnets A' and B' of the selected auxiliary switch, so as to move it into 35 electrical connection with the required main switch. He is then in a position to talk to the called subscriber. When through talking, he makes simultaneous electric circuits through both lines from his telephone, one of which 40 passes through the magnet D on his main switch and the magnet A' on his auxiliary switch and the other of which passes through the magnets B' B' on the switches. For convenience of reference I have marked the magnets A and B of the auxiliary switch as magnets A' and B', respectively, so as to distinguish their location from those of the main switch.

Before describing the circuits in detail I 55 will refer more particularly to the system of grouping involving auxiliary switches which I have illustrated. I have spoken of the contact-points on a switch as being divided into two groups of one hundred each. These two 60 groups may more particularly be referred to as “pairs” of groups and a reference to one group will equally represent a reference to the other group. Assuming for the moment that we are referring to the left-hand group of one 65 hundred contact-points, as illustrated in Fig.

1, this is divided into ten subgroups or vertical rows of contact-points each row of which represents a group of auxiliary switches in the exchange. For example, the first row of ten contact-points represents the first group 70 of ten auxiliary switches, which in turn are used to make connection to the first group of one hundred main switches. In like manner the second subgroup or vertical row of contact-points represents the second group of 75 auxiliary switches, which are used to make connection with the second group of one hundred main switches. The electrical connections are so made that any one auxiliary switch of the first group may be used to make 80 electrical connections with any one of the one hundred switches in the first group of main switches. In like manner any one auxiliary switch of the second group can be used to make connection to any one of the main 85 switches of the second group. The subscriber therefore selects the group that he wishes by moving his contact-maker laterally to the proper row, as has been described. He then advances his contact-maker on this row, and the 90 electrical connections are so made that the first idle auxiliary switch is automatically selected and isolated for his use, while at the same time his switch is automatically stopped in connection with that auxiliary switch. If another subscriber wishes to call some person in the same group, he cannot connect his main switch to this auxiliary switch until after the person who is using it has released it and permitted it to return to its normal position. 95 The manner in which these electrical connections are made is illustrated in Figs. 9, 10, and 11 much better than they can be set forth in words.

Returning now to the circuits previously 105 mentioned and describing them in detail, reference being had to Fig. 8, they will be as follows: The subscriber who wishes to call another closes a contact which we may call the “first” contact at his telephone, when a current flows as follows: X, 101, Tel. V, 50, 51, 52, 53, A, 54, 100, X. This energizes the magnet A and moves the shaft 28 upward one step, so as to bring the contact-point 57 into electrical connection with the contact-point 110 58. The contact-point 57 is in electrical connection with the base of the switch, so that any current which passes to the mechanism of the switch passes also to the contact-maker 57. The movement of the switch also moves the 115 contact-makers 66 and 92 away from their normal position, so that another switch cannot connect to the one which has commenced to call. He then closes another contact at his telephone, which we will call the “second” contact, when a current flows as follows: from 120 battery X, 101, Tel. V, 55, 56, A', 28, 57, 58, 59, 60, B, 61, X. This rotates the shaft 28 and moves the contact-makers 66 and 92 laterally one step into line with the next row or 125 130

subgroup of contact-points on his switch. He repeats this operation until his contact-makers have reached the position to connect with the required group. He then repeats the previous 5 operation of closing the first contact ten successive times, sending a series of impulses again through the magnet A to move the shaft 28 upward, and consequently the contact-makers 66 and 92 upward on the respective 10 rows of contact-points to which they were previously moved. In moving upward when the contact-makers reach a contact-point on the rows or subgroups which represent and are connected to an auxiliary switch not in 15 use there is immediately completed through those contact-points a circuit as follows: from battery Z, 62, 68, 63, C, 64, 65, 66, 67, 69, 70, A² of the selected auxiliary switch 71, 72, 73, G, 74, Z. This operates the magnet G so as 20 to move its armature-lever G' to connection with the contact 76, when a second circuit flows from battery X, 101, 75, G', 76, 77, 78, 79, A', 80, 100, X. This operates the magnet A' of the auxiliary switch, which is equivalent 25 to the magnet A of the main switch, and consequently moves its shaft and the corresponding contact-makers upward one step. To avoid confusion the contact-makers of the auxiliary switch are given numbers different 30 from those given for the contact-makers of the main switch, though they are, in fact, identical. The movement of the contact-makers breaks the connection 72 73 to the magnets G; but the movement of the armature-lever G' 35 closes this connection through a branch line between 83 and 84, so that the circuit through G is not actually broken until it is broken at the telephone. This branch circuit goes from 70 through G by way of 81, 82, 83, 84, 85, 73, G, &c. This acts as a safety for the magnet G. The operation of the magnet C after A has 40 been operated, so as to raise the collar on the upper end of the shaft 28 away from the lever J', permits J' to catch the armature-lever C², so as to hold 51 away from 52 and into 45 engagement with 86. For the sake of condensation the armature-lever C² and the contact-strip 51 are shown in Fig. 8 as being one and the same piece and marked 51. This operation 50 of the magnet C breaks the circuit of the magnet A, so that it cannot be operated another time from the telephone. To prevent this breaking of the circuit through the magnet A from being so quickly made as to interfere 55 with the operation of the parts there is a safety consisting of a short circuit for the magnet A, made by the connection or contact produced by 60 87 connecting to 88, thus holding the circuit complete to the magnet A until it is broken 65 at the telephone. When the connection is broken at the telephone, the line or circuit through the magnet A is opened in all directions, and the magnet A cannot then be operated until some further operations have been completed. It will be observed that in

the process just described the instant the contact-makers of the calling-switch reach a contact-point on the selected group which represents an auxiliary switch not in use the switch of the calling subscriber is automatically stopped at that connection and the selected auxiliary switch is automatically moved so as to break the connection by which it is initially moved from any calling subscriber, the consequence of which is that the selected auxiliary switch is isolated for the use of the person who has connected to it. When magnet A moves contact-makers 66 and 92 upward to connect with a busy auxiliary switch, the circuit, which would be closed through magnet C for an idle auxiliary switch, is open between 72 and 73, and contact 51 remains on contact 52, so that the circuit through magnet A is intact and the succeeding impulse carries contact-makers 66 and 92 beyond the busy auxiliary switch. It will be apparent that in making these ten contacts the only object is to make enough, so as to be certain to connect to one of the idle switches, and all contacts more than is necessary to pass the employed switches are blank contacts and have no effect whatever. After having made these ten contacts through the first contact at his telephone he then makes a contact at the second contact at his telephone, when a current flows as follows: X, 101, Tel. V, 55, 56, A², 90, D, 91, 92, 93, 94, 78, 79, A' of the selected auxiliary switch 80, 100, X. This moves the selected auxiliary switch one step farther with the contact-maker 72 into contact with the metal strip 95. He follows this by again making contact with his first contact, when a current flows as follows: X, 101, Tel. V, 50, 51, 86, (51 having been moved into connection with 86 by the 105 operation of the magnet C,) 65, 66, 67, 69, 70, A², 71, 72, 95, 96, 97, B', 98, 99, 102, 103, 80, 100, X. This moves the contact-makers laterally to successive rows or subgroups of 110 contact-points on the auxiliary switch and is repeated until the required group is reached. When the required group is reached, he closes the second contact at his telephone, when a current flows as follows: X, 101, Tel. V, 55, 56, A², 90, D, 91, 92, 93, 94, 78, 79, A' of the 115 selected auxiliary switch 80, 100, X. He repeats this so as to move the contact-makers upward until they reach connection to the required main switch. The talking-circuit will be as follows: Beginning at the left-hand telephone V of Fig. 8, which is assumed to be the calling-telephone, the circuit will be 55, 56, A², 90, D, 91, 92, 93, 94, 78, 104, 105, 106, 107 to the normal contact-point on the called switch 92, 91, D, 90, A², 56, 55, called Tel. 120 V', 50, 51, 52, 108, 109, 66, 110, 111, 112 to the auxiliary switch 72, 71, A², 70, 69, 67 back to 66 of the switch belonging to the calling telephone 65, 86, 51, 50 to the calling Tel. V. To release his own main switch and 125 130

the selected auxiliary switch, so that they will both return to their normal positions, he makes a simultaneous closure of both his first and second contact-points at his telephone. From the second contact results a current which flows as follows: X, 101, Tel. V, 55, 56, A², 90, D, 91, 92, 93, 94, 78, 79, A' of the selected auxiliary switch 80, 100, X. This operates D of the main switch, closing 59 to 114, and also operates A' of the auxiliary switch, closing 115 to 116. Closing 59 to 114 sends a current as follows: X, 101, Tel. V, 50, 87, 113, 114, 59, 60, B, 61, X. Closing 115 to 116 also sends a current as follows: 15 X, 101, Tel. V, 50, 51, 86, 65, 66, 67, 69, 70, 81, 115, 116, 97, B', 98, 102, 103, 80, 100, X. It will be seen from these circuits that in the main switch the magnets D and B have been successively and then simultaneously in operation, the result of which, as has been previously described, is to release the shaft 28 and permit the mechanism to return to its normal position. In the selected auxiliary switch it will be seen that the magnets A' and B', which 25 correspond to the magnets A and B of the main switch, have been similarly operated, the result of which is also to permit the mechanism of the auxiliary switch to return to its normal position. In case the calling subscriber has not succeeded in making connection to any auxiliary switch, because all of the auxiliary switches of the group happen to be in use at the time or for any other reason, then his two simultaneous circuits made at 30 his telephone would be confined to his own switch and would be as follows: X, 101, Tel. V, 50, 51, 52, 53, A, 54, 100, X; also, X, 101, Tel. V, 55, 56, 117, 118, 120, B, 61, X. This operates the magnets A and B and releases the 35 mechanism, as has been previously described.

In tracing the talking-circuit which has been described it will be observed that it does not at any point pass over the battery-line 100 or 101 nor over any line which is or can be 40 common to any other talking-circuit. It will therefore be evident that the talking-circuit is an isolated and purely metallic one from telephone to telephone. There is, however, a branch to the battery-line from each branch 45 of the talking-circuit between two telephones. This arrangement has been shown in condensed form in Fig. 12. The telephone at the left hand of the figure is assumed to have been the calling-telephone and the one at the right 50 hand to have been the called telephone. From the upper line between the contact-maker 92 on the main switch and contact-maker 104 on the auxiliary switch there is a branch 79 passing through the magnet A' to the battery-line 55 100. On the lower line between the called telephone and the contact-maker 66 there is another branch line, 53, going through the magnet A of the main switch to the battery-line 100. The magnets A and A' are identical magnets 60 on the main and auxiliary switches, re-

spectively. These magnets have the same electrical resistances, so that there is no tendency for any induced current to pass from the battery-line to either branch of the two lines between the two telephones. This will 70 be better understood by remembering that the magnets A and A' of all the telephones are similarly connected to the battery-line 100. If all of the magnets A were of less resistance than the magnets A', then when conversations 75 are being carried on between two or more pairs of telephones there would be a tendency for the current through the induction-coils of one pair of telephones to leak through the magnet A of one telephone to the line 100 80 and along this line to and through the magnet A of some other telephone, thus producing cross-talk. By making the resistances of A and A' the same the branches from the two sides of the talking-circuit to corresponding 85 sides of other talking-circuits will be balanced and the talking-current between one pair of telephones will not tend to induce a current to flow to or from either branch of either talking-circuit. 90

What I claim is—

1. In a switching mechanism for an automatic telephone-exchange, a driving-pawl and a holding-pawl, a shaft provided with a ratchet-wheel normally held in a position so as to be 95 out of engagement with said pawls, means for moving said shaft axially so as to bring said ratchet-wheel into line of engagement with both of said pawls, and means whereby further axial movement of said shaft will remove 100 said ratchet-wheel from line with the driving-pawl without disturbing its connection to the holding-pawl.

2. In an automatic telephone-exchange, a series of groups of main switches, each switch of 105 which is individual for a connected telephone, and a group of auxiliary switches for each group of main switches, said auxiliary switches being less in number than the main switches and each auxiliary switch being common for 110 connections from any main switch but common for connections to only the switches of the group to which it belongs, substantially as shown and specified.

3. In a telephone-exchange, a series of main 115 switches divided into groups, a smaller group of auxiliary switches for each group of main switches, each auxiliary switch consisting of a pair of contact-makers and devices for moving them into successive contact with a series 120 of pairs of contact-points, a pair of connections from each main switch of a group to a different pair of contact-points on each auxiliary switch for that group, and a pair of connecting lines from the pair of contact-makers 125 of each auxiliary switch to a position adjacent to the whole series of main switches, said pairs of connecting lines each being provided with branches connecting to corresponding pairs 130 of contact-points on the main switches.

4. In an automatic telephone-exchange, a series of main switches each of which is provided with a series of contact-points less in number than the number of such main switches, connections from the contact-points of each main switch, a series of auxiliary switches the number of which is equal to the possible connections extending from the contact-points of one main switch, a division of the main switches into groups, and a division of the auxiliary switches into an equal number of groups.

5. In an automatic telephone-exchange, the combination with a main switch provided with two groups of contact-points, the said groups being subdivided into rows, of a series of auxiliary switches connected to corresponding contact-points in the two groups on said main switch, a pair of contact-makers on the main switch and means for moving them to and over corresponding rows of contact-points in the two groups so as to connect the said contact-makers to one of said auxiliary switches, means for similarly moving the selected auxiliary switch, and means whereby such movement of the main switch and one of said auxiliary switches will serve to connect by a complete metallic circuit said main switch with any one of a series of other main switches the number of which is greater than the number of connections extending from the first-mentioned main switch.

6. In an automatic telephone-exchange, the combination with a series of auxiliary switches divided into groups, each member of a group being movable to electrical connection with any one of a more numerous group of main switches, of a series of such groups of main switches, two groups of contact-points on each main switch, said groups of contact-points being subdivided into vertical rows, and corresponding contact-points in corresponding rows being considered as a pair of contact-points, connections from each pair of contact-points to corresponding auxiliary switches, a pair of contact-makers on each main switch and means for moving them to positions opposite corresponding rows in the two groups of contact-points on such main switch, separate means for moving the contact-makers on a main switch over the rows of contact-points opposite to which they have been previously moved, and automatic means for stopping the movement of said contact-makers when they make contact with a pair of contact-points connected to an auxiliary switch which is at the time at its normal position.

7. In an automatic telephone-exchange, the combination with a series of like auxiliary switches divided into groups, each member of a group being movable to electrical connection with any member of a more numerous and corresponding group of main switches, of a series of such groups of main switches, two groups of contact-points subdivided into rows and located on each main switch, connections

from the corresponding contact-points in corresponding rows in the two groups to the different members of one of the groups of auxiliary switches, a pair of contact-makers on each main switch and means for moving them to different rows of contact-points so as to select any desired group of auxiliary switches, means for moving the contact-makers over the selected rows of contact-points and means for automatically stopping such movement so as to select the first unemployed auxiliary switch in the group of such switches connected to said rows of contact-points, and means for moving the selected auxiliary switch to electrical connection with any member of the corresponding group of main switches.

8. In an automatic telephone-exchange, the combination with a series of telephones, a main switch for each telephone, and a battery and magnets for operating said switches from their connected telephones, of a series of auxiliary switches less in number than the main switches, conductors extending in pairs from the main switches to the auxiliary switches, and other conductors extending in pairs from the auxiliary switches to the main switches.

9. In a telephone-exchange, a series of main switches divided into groups, a less numerous series of auxiliary switches divided into corresponding groups, on each auxiliary switch a pair of contact-points for each member of the group of main switches to which it belongs, pairs of connections between the pairs of contact-points and the corresponding main switches, a pair of contact-makers on each auxiliary switch adapted to be moved to successive contacts with pairs of contact-points, devices for so moving them, means for operating said devices from any main switch in the exchange so as to complete electrical connections from the operating-point to a selected member of the group of main switches to which the operated auxiliary switch belongs, and means for preventing a similar operation of the moved auxiliary switch from a second main switch while the said auxiliary switch is in possession of the first main switch.

10. A series of main switches, a series of pairs of insulated contact-points on each switch, a series of auxiliary switches less in number than the main switches, a series of pairs of contact-points on each auxiliary switch, a pair of wires extending from the first auxiliary switch with branches to the first pair of contact-points on each of the main switches, similar connections from each of the other auxiliary switches to corresponding pairs of contact-points on the main switches, a division of the auxiliary switches into groups, and separate pairs of connections from pairs of contact-points on each member of a group to a pair of normal contact-points on a different main switch whereby the said main switches are divided into groups corresponding to the groups of auxiliary switches.

11. In a telephone-exchange, the combination with a series of main switches each of which is individual for a connected telephone-station and each of which is provided with 5 pairs of electrical connections less in number than the number of such switches, of a series of auxiliary switches equal in number to the number of pairs of electrical connections on one main switch, and means whereby a movement of one main switch and one auxiliary switch will serve to establish telephonic connection between the moved main switch and any one of the other main switches in the exchange. 65
15. 12. In a telephone-exchange, the combination with a series of main switches divided into groups, and a less numerous series of auxiliary switches divided into corresponding groups, of electrical connections extending in 20 pairs from each main switch to all of the auxiliary switches in the exchange, return connections extending in pairs from each auxiliary switch to all of the main switches in the group corresponding to the group in which 25 the auxiliary switch is located, and means whereby a movement of one main switch and one auxiliary switch will serve to make telephonic connections between the moved main switch and any other main switch in the exchange. 70
30. 13. In an automatic telephone-exchange, a main switch provided with two groups of contact-points, a division of said groups into parallel rows, corresponding rows in the two groups being considered as pairs of rows and corresponding contact-points in a pair of rows being considered as a pair of contact-points, a pair of contact-makers on said switch and means for moving them to electrical connection with pairs of contact-points, an auxiliary switch connected to each pair of contact-points, said auxiliary switches being divided into groups corresponding to pairs of rows of contact-points on the main switch, a pair 45 of groups of contact-points on each auxiliary switch, and other main switches connected to pairs of contact-points on the auxiliary switches, said main switches being divided into groups corresponding to the groups of 50 auxiliary switches and having as many members in a group as there are pairs of contact-points on one auxiliary switch. 75
14. In a telephone-exchange comprising a series of groups of electrically-operated main 55 switches and a corresponding series of lesser groups of electrically-operated auxiliary switches, means for operating any main switch so as to cause a preliminary selection of any desired group of auxiliary switches, 60 and automatic means for selecting and isolating an idle auxiliary switch out of the preliminary selected group of auxiliary switches. 80
15. In a telephone-exchange comprising a series of groups of electrically-operated main 70 switches and a corresponding series of lesser groups of electrically-operated auxiliary switches, means for operating any main switch so as to cause a preliminary selection of any desired group of auxiliary switches, further means for operating the main switch 75 so as to cause the automatic selection of an idle auxiliary switch out of the preliminary selected group of auxiliary switches, and means for operating the automatically-selected auxiliary switch so as to select any one of the main switches located in the group of main switches which corresponds to the group of auxiliary switches in which is located the automatically-selected auxiliary switch. 85
16. A series of groups of main switches, a corresponding series of lesser groups of auxiliary switches, electrically-operated means by which any main switch may be moved to electrical connection with one of the auxiliary switches, and electrically-operated means by 90 which the selected auxiliary switch may be moved to electrical connection with any one of the main switches located in the group of main switches which corresponds to the group of auxiliary switches in which the selected auxiliary switch is located. 95
17. A series of groups of main switches, a lesser group of auxiliary switches apportioned to each group of main switches, electrical conductors from each main switch to all of the auxiliary switches, and return-conductors from each auxiliary switch of each group to all of the main switches located in the group of main switches to which it is apportioned. 100
18. A series of groups of main switches, a lesser group of auxiliary switches apportioned to each group of main switches, a group of contact-points on each main switch apportioned to each group of auxiliary switches, each contact-point of a group representing a different auxiliary switch in the group of auxiliary switches, conductors connecting each contact-point with the auxiliary switch which it represents, other contact-points on the auxiliary switches representing the main switches of the group to which the auxiliary switches are apportioned, and return-conductors connecting each contact-point on an auxiliary switch with the main switches of the group to which it is apportioned. 105
19. In an automatic telephone-exchange, a series of main switches, each of which is individual for a connected telephone-station, a telephone-station connected to each main switch, a lesser series of auxiliary switches 110 each of which is common for all stations, a series of contact-points on each main switch, one of which is the normal contact-point, other contact-points on each auxiliary switch, a direct connection from the normal contact-point on each main switch to a definite and correspondingly-located contact-point on each auxiliary switch, and other direct connections 115
- 120
- 125

from other contact-points of each main switch to corresponding magnets on all of the auxiliary switches.

20. In a telephone-exchange, a series of 5 main switches each of which is individual for a connected telephone-station, a lesser series of auxiliary switches, each of which is common for all stations, devices on each main switch for moving it to electrical connection 10 with successive auxiliary switches, and means by which a main switch so moved is automatically stopped when it reaches connection to an auxiliary switch that is in its normal position.

21. The combination with a series of movable main switches, and a series of movable auxiliary switches, of electrically-operated devices for moving a main switch to electrical connection with successive auxiliary switches, 20 and means by which the circuit for the electrically-operated devices will be automatically broken when the moved main switch reaches connection to an auxiliary switch which is in its normal position.

22. In a telephone-exchange, the combination with a series of main switches, and a series of auxiliary switches, each main switch being movable to connection with successive auxiliary switches, of devices by which upon 30 operating a main switch such main switch will be automatically associated in electrical connection with the first auxiliary switch which is at the time in its normal position.

23. In a telephone-exchange provided with 35 a plurality of switches any one of which may be used in establishing a talking-circuit between a calling and a desired one of the other stations of the exchange, means for automatically selecting an idle one of such switches, and means for operating the selected switch 40 for establishing such talking-circuit.

24. The combination with the stations of a

telephone-exchange, of a plurality of switches any one of which may be used in establishing a talking-circuit between a calling and a desired one of the other stations, means for automatically selecting an idle one of such switches, and automatic means for isolating the selected switch. 45

25. The combination with the stations of a 50 telephone-exchange, of a plurality of switches less in number than the number of stations in the exchange, and electrically-operated means by which an automatically-selected one of said switches may be used in establishing a talking-circuit between different stations. 55

26. The combination with the stations of a telephone-exchange, of a plurality of switches less in number than the number of stations in the exchange, means for automatically selecting 60 an idle one of said switches, and electrically-operated means for moving the selected switch so as to establish a talking-circuit between two stations. 65

27. The combination with the stations of a telephone-exchange, an electrically-operated device for each station, and connections from each station to its device, of a series of switching mechanisms less in number than the number of stations, means controlled from any 70 station for moving its electrically-operated device so as to automatically select and make connections to an unemployed one of said switching mechanisms, and means controlled from the same place for moving the selected 75 switching mechanism to connection with the electrically-operated device of any one of a plurality of other stations. 75

Signed at Chicago, Illinois, this 20th day of April, 1900.
